ALFRED R. WOOD, OF BRIDGEPORT, CONNECTICUT, ASSIGNOR TO THE SINGER MANUFACTURING COMPANY, A CORPORATION OF NEW JERSEY.

SEWING-MACHINE WORK-CLAMP.

1,228,863.

Specification of Letters Patent. Patented June 5, 1917.

Application filed November 16, 1912. Serial No. 731,705.

To all whom it may concern:

Be it known that I, ALFRED R. WOOD, a citizen of the United States, residing at Bridgeport, in the county of Fairfield and State of Connecticut, have invented certain new and useful Improvements in Sewing-Machine Work-Clamps, of which the following is a specification, reference being had therein to the accompanying drawings.

10 This invention has for its object to provide convenient and effective means for presenting to suitable fastening means, such as overseaming stitch-forming mechanism, small articles constructed of metal or other 15 hard material impenetrable by the fastening implement to be fastened to a body fabric. It is intended primarily for attachment to a member of a hose supporter of one of the parts of a fastener by means of which 20 the supporter is secured in place upon the wearer.

The improvement is preferably embodied in the traveling work-clamp of a tacking machine, and comprises a holder adapted to receive the fastener and constituting a laterally movable section of a work-gripping jaw afforded by one of the separable work-clamping members. In its preferred form, the holder comprises a plate pivotally 30 mounted upon the upper work clamp-member and formed in its lower face with a recess or cavity conforming in shape with a portion of the article to be sustained thereby and overlapped by a spring retaining 35 plate whose lower face is substantially flush with the serrated work-gripping face of such clamp-member and beyond which another portion of the article projects into the needle aperture of the clamp within the 40 range of action of the stitch-forming mechanism by means of which it is secured upon the body fabric gripped by the work-clamp in conjunction with said holder. Means are provided for retracting the holder from 45 operative position upon its sustaining clamp-member without altering the relative positions of the separable clamping-members for convenience in introducing a fastener and for thereafter shifting the same into operative position to move the fastener into the 50 range of action of the stitch-forming mechanism.

In the accompanying drawings, Figure 1 is a perspective view of a portion of a sewing machine bed-plate provided with a trav-

eling work-clamp having a fastener-holder embodying the present improvement, and Fig. 2 a plan of the work-gripping members of the clamp and the fastener-holder. Fig. 3 is a perspective view, taken from the 60 lower side, and showing the upper work-clamp member and the holder sustained thereby in operative relation therewith. Fig. 4 is a perspective view of the spring-retaining plate of the holder. Fig. 5 is a 65 diagrammatic view representing the overlapped tacking stitches by means of which the fastener is secured to the fabric. Fig. 6 is a perspective view of a member of the hose supporter having a fastener secured 70 thereto in accordance with the present invention.

The improvement is shown embodied in a Singer straight-buttonhole machine such as that represented in the United States Patent 75 No. 806,231, of December 5, 1905, and in practice has the side-shifting means for the work-clamp disconnected from the feed-cam or otherwise rendered ineffective so that the clamp has a to-and-fro longitudinal movement only to space the stitches, whereby an initial zigzag fastening seam *a* is produced by a feeding movement in one direction and a superposed fastening seam *b* is produced by the movement of the clamp in the opposite direction, as represented in Fig. 5.

The sewing machine bed-plate 1 is shown provided with a transverse channel in which is fitted the cross slide-plate 2 which in the present instance is restrained by suitable 90 means, as by screws 3, from transverse movement. The plate 2 has a seat upon which rests the longitudinal slide-plate 4 which is provided along its edges with rabbets 5 entered by tongues formed upon the edges of strips 6 secured by screws 7 upon the plate 2. The slide-plate 4 has an elongated opening 8 embracing the needle-throat 9 secured by screws 10 upon the cross slide-plate 2 and provided with the usual elongated needle-aperture 11. The marginal portions of the upper face of the slide-plate 4 constitute the lower jaw of the work-clamp whose upper jaw consists of the serrated face 12 of the upper clamp-member 13 which is formed 95 with the lateral arm or extension 14.

The member 13 is sustained by pivotal screws 15 within a yoke 16 mounted upon the screw-pin 17 sustained by the apertured lug 18 of the rocking arm 19 attached to 110

a block 20 having depending ears pivotally connected by means of the transverse pin 21 with a bracket 22. The bracket 22 is mounted upon the foot-plate 23 which is 5 adjustably secured by screws 24 upon the supporting plate 25 having a lateral extension 25' rigidly secured upon the slide-plate 4. The foot-plate 23 has the usual post 26 passing through a suitable aperture in the 10 clamp-arm 19 and surrounded by a spring 27 interposed between the thrust-nut 28 thereon and a thrust-plate 29 resting upon the clamp-arm and by means of which the upper clamping member 13 is normally 15 pressed upon the work interposed between the same and the lower clamping member 4. The clamp-arm 19 has a rearward extension 30 to which is attached the chain 31 connected with a treadle by means of which the 20 upper clamping member may be lifted for introduction or removal of the work. The upper clamping member 13 has the usual aperture 13' through which works the needle 32 mounted in the reciprocating and laterally jogging needle-bar 33 of the stitch-forming mechanism.

The arm 14 is apertured in its outer portion to afford a bearing for the vertical rocking pin 34 having fixed upon its lower end 30 the thin arm or plate 35 which is shown provided at the outer end of its lower face with the substantially U-shaped or arched fastener receiving groove 36, the outer edge of the holder-plate being suitably beveled to direct the fastener into the groove 36. The recessed end portion of the holder-plate 35 normally enters a clearance space 13" formed by cutting away a portion at one corner of the lower or operative face of the upper 35 clamping member. Secured to the bottom of the holder-plate 35 by means of screws 37 is the spring-plate 38 whose free outer end overlaps the plate 35 and affords a yielding cover for the fastener groove 36, as represented in dotted lines in Fig. 3. In practice the lower face of the spring-plate 38 is substantially flush with the serrated lower face of the clamp-member 13 and thus constitutes a section of the upper work-gripping jaw 50 when in operative position, as represented in Fig. 3.

As will be readily understood by reference to Fig. 1, the article holder 35 38, while pivotally mounted upon the upper clamp 13 55 can be moved independently of it without disturbing its relative position with respect to the lower clamp 4.

The rounded end of the holder-plate adjacent the fulcrum-pin 34 is provided with 60 spaced peripheral notches 39 and 40 adapted to be entered alternately by the downturned end portion 41 of a detent-spring 42 passing through a notch in the edge of the arm 14 and having its opposite end formed in an 65 eye secured upon the top of the arm 14 by

the fastening screw 43. Secured upon the upper end of the rocking pin 34 by means of set-screws 44 is the hub 45 of a finger-lever, 70 46 by means of which the pin 34 may be turned to shift the holder-plate from operative position represented in Figs. 2 and 3 to retracted position shown in Fig. 1, the part 41 of the detent-spring snapping into one or the other of the notches 39 and 40 of the holder-plate to retain it yieldingly in 75 either of such extreme positions, the head 47 of the stop-screw tapped into the lower face of the arm 14 engaging the edge of the holder-plate 35 when in operative position.

To the extension 25' of the supporting 80 plate 25 is adjustably secured by means of the screw 48 passing through a slot 49 the shank 50 of a yoke-shaped guide 51 having at its extremities the upturned guide-lips 52 and 53, the former of which is of angular 85 shape, to locate the fabric for reception of the fastener in the desired position relative to the stitch-forming mechanism.

To prepare the device for a stitching operation, the upper work-clamping member is 90 first raised by drawing down the chain 31 and the holder 35 38 swung outwardly by means of the finger-lever 46, as represented in Fig. 1. The mouth of the holder is thus 95 presented at one side of and entirely free from the upper clamping member, which enables the operator to readily introduce the fastener *t*. The rounded nose of the substantially triangular fastener is then inserted between the ends of the holder-plate 35 and 100 spring-plate 38 which are separated sufficiently to admit the fastener within the groove 36 in which it is yieldingly confined against displacement by means of the spring-plate 38. The holder is then returned to initial operative position, as represented in 105 Figs. 2 and 3, with the bar *t'* of the fastener arranged at substantially the center of the needle-aperture 13' of the upper clamping member and lying across the needle-aperture 11 of the throat-plate, after which the fabric *f* is inserted with its edges in contact 110 with the guide-lips 52 and 53 and the upper clamping member permitted to descend upon the work under the action of the spring 27. 115

The stitching mechanism being set in operation, a line of overseam stitches is produced during the initial feed of the clamp beginning at one end of the bar *t'* and embracing the same substantially throughout 120 its length, after which a second series of 125 stitches is superposed in the retrograde feeding movement of the clamp to initial starting position, thereby securely attaching the fastener to the fabric, as represented in Fig. 6.

While the holder is represented herein as constructed to receive the eye member of a hook-and-eye fastening for hose supporters, 130 it is evident that the holder may be readily

adapted to sustain any small articles for attachment to a body fabric secured in the work-clamp, such as small buttons or spangles.

5 While the embodiment shown and described herein is considered the preferable one, it is evident that the present improvement is susceptible of material modification in construction and arrangement of parts 10 within the scope of the invention.

Having thus set forth the nature of the invention, what I claim herein is:—

15 1. A work-clamp for sewing machines comprising separable clamping members, a fulcrum-pin carried by one of said members and disposed transverse to its work-engaging face, and an article-holder journaled upon said pin and adapted for movement thereon relatively to both of said 20 clamping members and in a direction substantially parallel with their work-engaging faces.

25 2. A work-clamp for sewing machines comprising separable clamping members whose adjacent faces afford opposed work-gripping jaws, and an article-holder sustained by one of said members and affording a section laterally movable independently of the latter's work-gripping jaw with 30 which said holder has a rigid connection whereby they are compelled to perform in unison opening and closing movements toward and from the other of said clamping members.

35 3. A work-clamp for sewing machines comprising separable clamping members whose adjacent faces afford opposed gripping jaws, a fulcrum-pin carried by and disposed in angular relation with the work- 40 engaging face of one of said members, an article-holder having an aperture to receive said pin and having its exposed face flush with that of said member, and means for shifting said article-holder laterally relatively to both clamping members and sub- 45

stantially parallel with their work-engaging faces.

4. A work-clamp for sewing machines, comprising separable clamping members, and an article holder movable into and out 50 of a position between the opposed faces of said clamping members in a direction substantially parallel with said faces.

5. A work-clamp for sewing machines comprising separable upper and lower 55 clamping members with the clamping face of the upper member partially cut away to form a clearance space, a fulcrum-pin sustained by the upper clamping member, a holder-arm having an aperture to receive 60 said pin and provided with a yielding fastener-cavity and adapted to lie within the clearance space of said upper clamping member, and means for shifting said holder-arm into and out of said clearance space so 65 that said holder-arm will coöperate with said separable members in their clamping action upon the work.

6. A work-clamp for sewing machines comprising separable upper and lower 70 clamping members, a fulcrum-pin sustained by the upper clamping member, and an article-holder having an aperture to receive said pin and provided with a cavity to receive an article, a spring-plate secured to 75 the article-holder and overlying the cavity therein, means for shifting said article-holder laterally relatively to and substantially parallel with the work-engaging face of the upper clamping member, and a de- 80 tent spring secured upon said upper clamping member and adapted to enter spaced notches formed in said article-holder.

In testimony whereof, I have signed my name to this specification, in the presence of 85 two subscribing witnesses.

ALFRED R. WOOD.
